UNITED STATES PATENT OFFICE.

PETER ERNEST BRULATOUR, OF COYTESVILLE, NEW JERSEY.

ROTARY INTERNAL-COMBUSTION ENGINE.

Application filed January 17, 1921. Serial No. 437,872.

To all whom it may concern:

Be it known that I, PETER ERNEST BRULATOUR, a citizen of the United States, residing at Coytesville, county of Bergen, State of New Jersey, have invented a certain new and useful Rotary Internal-Combustion Engine, of which the following is a specification.

This invention is an internal combustion engine embodying a rotor adapted to be driven by the energy developed by the combustion of successively fired charges of a combustible agent, whereby a continuously acting direct drive is obtained for the shaft, the weight and dimensions of the engine are minimized, and a corresponding simplification of the mechanism is attained by the omission of parts without loss of function.

My engine is characterized by an organization of mechanisms wherein provision is made for the intake, compression, ignition and scavenging of the motive fluid in accordance with the four cycle mode of procedure available in internal combustion engines of standard construction; but in this invention such mode of utilizing the motive fluid is attained in association with a rotor carried directly by the engine shaft.

The engine embodies an annular chamber of a desired cross sectional form, a shaft positioned in coaxial relation to said chamber, said shaft being axially bored for a part of its length so as to present a tubular member at one end thereof, a rotor operable within said annular chamber and carried by said shaft, a plurality of inlet ports to said chamber, a plurality of exhaust ports in communication with the chamber, an intermittently operable abutment positioned within said chamber and in co-operative relation to said rotor, and means for accelerating and retarding said abutment so as to time its operation in synchronism with the travel of the rotor for effecting the operation of compressing the charges of the explosive mixture, affording a pressure head for the action of the gases evolved by the ignition of said mixture charges, and of scavenging the spent gases by expelling the latter through the exhaust ports.

A preferred means for actuating the abutment in time with the rotor includes a tappet shaft journaled in the tubular member of the engine shaft and to which tappet shaft is affixed said abutment, a cam shaft journaled in a bearing provided on the en-

gine balance or fly wheel which is mounted on the tubular portion of the engine shaft for imparting thereto the required momentum to effect steady running, a cam of a desired contour carried by the cam shaft, a tappet rigid with the tappet shaft and contacting with said cam for periodically retarding the abutment and in like manner imparting to said abutment an accelerating rotative movement whereby the abutment is impelled to travel with reference to the rotor, and gearing for imparting on the rotation of the fly wheel the required motion to the cam shaft, said gearing including a fixed master gear on the engine frame and a pinion on the cam shaft.

Provision is made for minimizing the leakage of the high pressure gases from the annular rotor chamber by appropriate packing rings on the rotor and the abutment, which packing rings travel within complementary packing grooves provided within the casing or cylinder for the annular chamber. Furthermore, leakage of the gases in the interval between the abutment and the rotor is minimized by the provision of a packing member which is attached to and movable with the abutment and is arranged to travel or play within a slot of the rotor, said packing member closing the space intervening between the rotor and the abutment.

Other functions and advantages of the invention will appear from the following description taken in connection with the drawings, wherein—

Figure 1 is a vertical cross sectional elevation taken in the plane of the engine shaft.

Figure 2 is a vertical cross section partly in elevation and in a plane at right angles to Figure 1.

Figure 3 is a view in side elevation partly broken away illustrating the means for imparting movement to and retarding the shaft for the abutment; and

Figure 4 is a perspective view of the rotor and a part of the engine shaft.

The engine is constructed with a cylinder A having a base a, said cylinder constituting an annular chamber B for the rotor C. The cylinder is divided vertically in the plane of the axis of the rotor, thus producing complementary members A' each comprising a half portion of the chamber B and of base a, which complementary members are solidly secured together in abutting relation.

tion by appropriate bolts b and are provided with suitable packings b' . The members comprising the cylinder are constructed with water chambers D that jacket the working chamber B for the circulation of a cooling medium, and said members are provided also with bearings e for the rotor shaft E , the latter being positioned in coaxial relation to the working chamber B . Said shaft E is tubular for a part of its length, as at e' , and is provided with an arcuate slot e'' , and within the tubular part e' of said engine shaft is journaled a tappet shaft F , one end portion of which protrudes from the engine shaft, see Figure 1.

The cylinder is provided at diametrically opposite points with ignition means, two being shown as spark plugs $G G'$ in Figure 2. Said cylinder is provided also with inlet ports 1, 2, and 3, 4, two in a set of ports and the ports of each set being radial to the axis of the chamber B , and the sets of ports being intermediate the ignition plugs $G G'$. Adjacent the inlet ports, the cylinder is provided with two sets of exhaust ports 5, 6, 7, and 8, 9, 10, three ports in a set, and the ports of each set being concentric to the axis of rotation of the rotor C .

Rotor C is preferably a casting of the form shown more particularly in Figures 2 and 4, the body portion c being in one piece with a piston head c' and with a shank c'' . The shank c'' is solid with engine shaft E at the tubular part e' thereof, thus making the rotor fast with said shaft for unitary motion therewith. The piston head c' is of form and dimensions corresponding to the cross section of chamber B , said head having appropriate packings c^3 for tight frictional contact with the wall of the chamber B . In the rotor body c is a curved slot h , and a plurality of grooves h' , the latter receiving the annular packing rings h^2 provided in the abutting faces of the complementary cylinder members A' , said packing rings being concentric to the engine shaft, see Figure 1.

On the tubular portion e' of the engine shaft is a balance or fly wheel H , with the usual heavy rim, said fly wheel having a shaft bearing i for the cam shaft I , whereby said cam shaft is mounted on the fly wheel for rotation therewith and it is rotatable freely on its axis and within the bearing i . A cam J is secured fixedly to the shaft I at one end, whereas a gear pinion K is made fast to the other end of the cam shaft, said pinion meshing with a fixed gear L made fast to the engine cylinder, see Figures 1 and 3. As will be noted by reference to Figure 3, the cam is approximately double circular in form with indented notches j in opposite sides, and with said cam co-operates a tappet M . Said tappet is fast or rigid with the tappet shaft

F at the protruding part thereof. The tappet is a curved arm positioned in such relation to the cam that the required clearance is attained, said tappet being provided at its free end with a roller shoe m that tracks on the peripheral portion of the cam.

O is the abutment in the form of a head provided with packings to have the required frictional contact with the surface of the chamber B . The abutment head is integral with a shank o extending radially to the tappet shaft F and fast therewith, said abutment and the tappet shaft being unitary for rotative movement. The shank of said abutment is free to play in the curved slot e'' of the engine shaft, whereby the abutment is capable of a limited movement with respect to the rotor. Said shank o is provided with grooves o' for the reception of the annular packing rings h^2 , the latter co-operating with the shank c'' and body c of the rotor C and with the shank o of the abutment so as to afford the required gas tight contact between the rotor and the abutment with the complements of the cylinder.

The rotor C and abutment O are rotatable within the chamber, but the movements are independent, the rotor being driven by the energy of the charges of combustible exploded within the chamber between the abutment and the rotor, whereas the abutment is driven periodically by the rotative movement of the cam which is carried by the fly wheel and is geared to the fixed gear, although the cam acts in the intervals between the driving impulses to retard the tappet, its shaft and the abutment. For closing the gap intermediate the rotor and the abutment at all times, and particularly at the time when the rotor is driven by the ignited gases away from the abutment, I provide a gas check member P in the form of a curved plate. This plate is fast with the abutment and projects for a substantial distance beyond the shank o thereof, said plate being curved concentrically to the cylinder and said plate being positioned for sliding movement in the slot h provided in the body member c of the rotor. The plate travels in the outer packing ring channel h^2 between the complements A' of the cylinder and spans the space intermediate the abutment and the rotor so as to minimize the leakage of the gases toward the engine shaft and the tappet shaft.

In operation and with the parts in the full line position of Figure 2, the combustible mixture is compressed in the space of chamber B intermediate the abutment O and the rotor C . The ignition of the combustible mixture by plug G' fires the charge, the expansive energy of which drives the rotor to the right so as to successively open the set of exhaust ports 8, 9, 10. At the period of ignition, the abutment is retarded

by the contact of the tappet arm M with one indentation j of cam J, but as the rotor approaches the set of exhaust ports 8, 9, 10, the cam J rotated by the gearing and carried by the fly wheel acts to turn the tappet arm and its shaft so as to impart rotative movement to the abutment whereby the latter is driven at an accelerated speed with respect to the rotor, the effect of which is to expel the spent gases through the ports 8, 9, 10. As the rotor reaches the dotted line position of Figure 2, its travel opens the intake ports 3, 4, by the time the abutment reaches the dotted line position to close exhaust port 10, and the continued movement of the rotor draws in the charge through ports 3, 4, the abutment being at this time retarded by the cam and tappet in the dotted line position, whereupon the cam and tappet are actuated by the rotation of the fly wheel and the gearing to impart accelerated speed to the abutment in order to move the abutment closer to the rotor by the time the latter passes the spark plug G, which acceleration in the travel of the abutment O relatively to the rotor operates to compress the charge of combustible admitted by the ports 3, 4, so that the charge is under pressure when fired by the plug G, at which period the abutment is again retarded by the cam whereas the rotor is free to drive by the explosive energy of the ignited charge.

The cycle of operations described is carried on indefinitely for imparting rotative movement continuously to the rotor and the engine shaft, the rotation of the latter being steadied by the balance wheel, but while the rotor and the shaft are driven continuously by the explosive effect of the gases, the action of the abutment is intermittent, the same being retarded at the periods of ignition and the rotative movement of which abutment is accelerated with respect to the rotor, whereby said abutment performs several distinct functions, (a) when retarded, it acts as a head for resisting the pressure of the gases, (b) in its forward rotated movement following the ignition of the gases, the abutment sweeps the gases out of the chamber and expels them through the exhaust ports; and following the opening of the intake ports and the subsequent acceleration of the abutment, the latter compresses the charge of combustible mixture confined in the space between the rotor and the abutment, as a result of which the fresh charge is compressed by the time the rotor and the abutment assume the required positions relatively to the ignition plug.

In my engine the rotor is in fixed relation to, and is carried directly by, the engine shaft, said rotor being in a position substantially radial to the axis of the engine shaft and said rotor moving in a circular

path concentric to the axis of the engine shaft. The charges of combustible mixture are ignited by spark plugs which are so positioned within the annular chamber that the expansive force of the ignited charges is exerted in a direction substantially at a right angle to the axis of the engine shaft. The rotor is positioned and actuated to exert a direct leverage on the engine shaft, the relation of the rotor to the shaft being such as to apply a long leverage action.

Having thus fully described the invention, what I claim as new and desire to secure by Letters Patent is:

1. In an engine of the class described, an annular chamber provided with inlet ports and with exhaust ports, a tubular engine shaft, a rotor fast with said engine shaft, a tappet shaft journaled in said tubular engine shaft, an abutment fast with the tappet shaft and movable within said annular chamber with respect to said rotor, a revolvable member fast with the engine shaft, a cam mounted on the revolvable member for rotation therewith and capable of axial rotative movement, a tappet fast with the tappet shaft and contacting said cam, and means for imparting axial rotative movement to said cam whereby the cam and the tappet devices co-operate in retarding and accelerating the movement of the abutment relatively to the rotor.

2. In an engine of the class described, an annular chamber provided with inlet ports and with exhaust ports, a tubular engine shaft, a rotor fast with said engine shaft, a tappet shaft journaled in said tubular engine shaft, an abutment fast with the tappet shaft and movable within said annular chamber with respect to said rotor, a balance wheel fast with the engine shaft, a cam shaft mounted on said balance wheel for rotation therewith and capable of independent axial rotation, a cam on said cam shaft, a tappet fast with the tappet shaft and in contact with said cam, and means operable by the rotative movement of the balance wheel for imparting rotative movement to the cam shaft and to the cam whereby the cam and the tappet devices co-operate in retarding and accelerating the movement of the abutment relatively to the rotor.

3. In an engine of the class described, an annular chamber provided with a plurality of series of intake ports positioned radially to the axis of the chamber and with a plurality of series of exhaust ports concentric to said chamber, a shaft, a rotor fast with the shaft and movable within said chamber relatively to the radial intake ports and the arcuate exhaust ports, an abutment positioned within the chamber for movement relatively to the rotor, and means for periodically accelerating and retarding the abutment, said means including a tappet shaft

- coaxial with the first named shaft, a cam positioned exteriorly to the chamber, means for rotating said cam, and a tappet carried by the tappet shaft and tracking said cam.
4. In an engine of the class described, an annular chamber, an engine shaft, a rotor fast with said engine shaft, a balance wheel rotatable with the engine shaft, a cam shaft mounted on the balance wheel for rotation therewith and capable of independent axial rotation, a cam fast with said cam shaft, a tappet shaft, a tappet fast with the tappet shaft and contacting with said cam, and means operable by the rotative movement of the balance wheel for imparting rotative movement to the cam shaft and the cam whereby the tappet devices control the movement of the abutment relatively to the rotor.
5. In an engine of the class described, an annular chamber provided with inlet and exhaust ports and with ignition means, an engine shaft having a tubular portion, a rotor fast with said shaft, a tappet shaft journaled in said tubular portion of the engine shaft, an abutment fast with the tappet shaft and movable within the chamber relatively to the rotor, a balance wheel fast with the engine shaft, a cam carried by the balance wheel, means for rotating the cam during its travel with the balance wheel, and a tappet fast with the tappet shaft and tracking the cam whereby the abutment is periodically actuated and is retarded at the periods of ignition of the combustible charges.
6. In an engine of the class described, an annular chamber provided with inlet and exhaust ports and with ignition means, an engine shaft having a tubular portion, a rotor fast with said shaft, a tappet shaft journaled in said tubular portion of the engine shaft, an abutment fast with the tappet shaft and movable within the chamber relatively to the rotor, a balance wheel fast with the engine shaft, a cam carried by the balance wheel, gearing for rotating the cam continuously during the movement of said cam with the balance wheel, and a tappet fast with the tappet shaft and tracking the cam for periodically imparting movement to the abutment relatively to the rotor and for retarding said abutment within the chamber in the intervals of its periodic movement.
7. In an engine of the class described, an annular chamber provided with inlet ports and with exhaust ports, an engine shaft having a tubular portion, a rotor fast with the engine shaft, an abutment positioned within the chamber for movement relatively to the rotor, a tappet shaft journaled in the tubular portion of said engine shaft, said abutment being fast with the tappet shaft, a balance wheel on the engine shaft, a fixed gear, a cam shaft journaled on the balance wheel, a gear fixed to the cam shaft and meshing with the fixed gear, a double cam fast with the cam shaft, and a tappet tracking said cam and fast with the tappet shaft for imparting movement to the abutment and for retarding said abutment.

In testimony whereof I have signed my name hereto the 14th day of January, 1921.

PETER ERNEST BRULATOUR.
